SUCTION CLEANER

Robert S. Boyle, Akron, Ohio, and Charles H. Taylor, Springfield, Mass., assignors to The Hoover Company, North Canton, Ohio, a corporation of Ohio

Application December 23, 1938, Serial No. 247,430

15 Claims. (Cl. 15—183)

The present invention relates to suction cleaners in general and more particularly to new and improved rotary agitator with radially adjustable brush elements. More particularly the invention comprises a rotary agitator for a suction cleaner which includes helically extending brush elements which are subjected to wear in use, means being provided by which the brush elements can be adjusted radially to compensate for decrease in bristle length after prolonged use has made such adjustment necessary.

It is an object of the present invention to provide a new and improved suction cleaner. It is another object of the invention to provide a new and improved rotary agitator for a suction cleaner. A still further object of the invention is to provide a rotary agitator for a suction cleaner which includes a helical brush which is radially adjustable. A still further object of the invention is to provide new and improved means by which a helically extending brush in a rotary agitator for a suction cleaner can be radially adjusted to compensate for decrease in bristle length occasioned by wear. A still further object of the invention is to provide a helically extending brush element in a rotary agitator which includes a rigid back and flexible bristle elements, there being cooperating seats upon the brush back and upon the agitator body which can be manually selected to vary the height of the brush relative to the agitator body. Still another object of the invention is to provide a rotary agitator for a suction cleaner in which a helical brush is radially adjustable relative to the agitator body by manual adjustment of means on the agitator body. A still further object of the invention is to provide a rotary agitator in which a helical brush is adjusted to give the desired bristle extension by moving the brush element longitudinally within the brush seat. These and other more specific objects will appear upon reading the following specification and claims and upon considering in connection therewith the attached drawings to which they relate.

Referring now to the drawings in which preferred embodiments of the present invention are disclosed and in which the same reference character refers to the same part throughout:

Figure 1 is a side elevation of a suction cleaner embodying the present invention, a section being shown through the forward part of the machine to illustrate the rotary agitator positioned within the nozzle;

Figure 2 is a side elevation of the suction cleaner rotary agitator constructed in accordance with

the first embodiment of the present invention and embodying helically extending bristle elements;

Figure 3 is a longitudinal section taken along the helical brush element;

Figure 4 is a transverse section through the agitator upon the line 4—4 of Figure 2;

Figure 5 is an enlarged view in perspective of the agitator with a portion of the body thereof broken away to illustrate the adjustable brush positioned therein;

Figure 6 is an illustration of the helical brush positioned by the adjusting means in the "new brush" position;

Figure 7 is a view similar to Figure 6 with the brush positioned in the "old brush" position;

Figures 8 and 9 illustrate the manually adjustable bar positioned in the bottom of the brush seat by which the user can adjust the brush position;

Figure 10 is a view similar to Figure 6 and shows a second preferred type of adjustment in which the brush is moved longitudinally in its seat to accomplish the adjustment;

Figure 11 is a section through the brush and its seat upon the line 11—11 of Figure 10;

Figure 12 is a section upon the line 12—12 of Figure 10;

Figure 13 is a view similar to Figures 6 and 10 and illustrates a third preferred form of the brush adjustment;

Figure 14 is a view in perspective of the adjustment bar which is manually movable in the brush seat to accomplish the adjustment;

Figure 15 is a section upon the line 15—15 of Figure 13; and

Figure 16 is a fragmentary view of the indicating means for the adjuster looking in the direction indicated by the arrows 16—16 of Figure 13.

In the modern suction cleaner foreign material is dislodged from a surface covering undergoing cleaning by a rotary agitator and is removed by the stream of air drawn through the machine by the suction-creating means thereof. The preferred form of rotary agitator embodies both rigid beating elements and flexible brush elements. The former elements positively vibrate the surface covering and effectively dislodge therefrom the embedded foreign material while the latter elements effect a pile-straightening function. According to the present invention helically arranged removable brush elements are embodied in the rotary agitator and are adjustable relative to the agitator body to compensate

for the decrease in bristle length which results from cleaner use. Axially extending brush elements in such agitators have heretofore been provided which are radially adjustable but up to the present time no readily removable helically extending brush elements have been provided with suitable and satisfactory adjusting means.

Referring again to the drawings, and to Figure 1 in particular, a modern suction cleaner is illustrated in which a main casing 1 includes a nozzle 2, a fan chamber 3 having an eye 4, an interconnecting air passageway 5, and an exhaust outlet 6. Upon the casing is a motor casing 7 within which is positioned an unshown driving motor, the shaft 8 of which extends downwardly through the fan chamber 3 where it carries a suction creating fan 9 effective in cleaner operation to draw air into the nozzle 2 between the surface-contacting lips 10 and 11, rearwardly through the air passageway 5, and through the eye 4 into the fan chamber 3. From the fan chamber 3 the air is exhausted through the outlet 6 into the filter bag 12 which is removably attached to the outlet 6 by manually operable means 13. This air stream passing through the cleaner removes any foreign material from a surface covering under-cleaning which has been dislodged by the rotating agitator positioned in the nozzle and indicated generally by the reference character 15. This agitator is rotated by means of the power-transmitting belt 16 which connects to the pulley 17 positioned at the lower end of the motor shaft 8.

The cleaner is movably supported upon an underlying surface by front wheels, indicated by the reference character 18, and by rear wheels, indicated by the reference character 19, and, also in the manner of the usual cleaner, a pivoted handle 20 is provided by which the operator may exert the propelling force necessary to operate the machine. The cleaner in its general arrangement is common and well known even to the nozzle-height-adjusting means 21 by which the rear wheels 19 may be raised and lowered to effect a vertical adjustment of the nozzle 2 and the agitator 15 relative to a surface covering undergoing cleaning.

The rotary agitator 15 comprises an elongated cylindrical body 24 which is provided substantially midway of its length with a circumferential groove 25 which functions as a pulley to seat the power-transmitting belt by which the agitator is driven. Agitator body 24 is provided with helically extending recessed brush seats 26 which may be integrally formed or formed of separate elements secured fixedly in place therein as by welding. Within each brush seat 26 is removably positioned a helical brush element 27 hereinafter more fully disclosed. Fixedly secured upon the surface of agitator body 25 and extending helically are rigid beater elements 28 which cooperate with the brush elements 27, in the operation of the agitator, to dislodge and clean the surface covering undergoing cleaning.

Cylindrical agitator body 24 is rotatably supported at each of its ends upon a shaft 29 by an end plate 30 which seats a ball bearing 22. A thread guard 23 carried by the shaft 29 adjacent each end plate 30 overlies that member to provide a bearing protector which prevents the accumulation of foreign material and dirt.

The brush element seat 26 is positioned within the normal contour of the cylindrical body 24

and extends helically, preferably in alignment with a rigid beating element 28 upon the opposite side of the pulley 25, as illustrated in Figure 2. The side walls of the brush seat, in any given transverse plane of the agitator body, as illustrated in Figure 4, extend parallel to a radial line through the brush seat center in that plane, and the bottom wall of the seat extends perpendicular thereto in any given plane. The brush element 27 comprises a rigid back 31 which is shaped exactly as the brush seat 26 but is slightly narrower than that seat thereby providing a small clearance. The back 31 is fabricated of an outer relatively large U-shaped channel member 32, the bottom of which is closed by an inner relatively small U-shaped channel member 33. The flexible brush bristles 34, 34 etc. are secured to member 33 and extend upwardly and through the top of the large U-channel member 32.

The opposite ends of the brush back 31 are provided on their undersides with series of steps or seats 35, 35 which slope in the same direction at the opposite ends of the back. The steps 25 or seats at the two ends are equi-spaced and identical in arrangement. As a matter of fact there are two series of steps at each end of the brush back, one series on each side wall of the U-channel members, but, as the two series of 30 steps at each end of the back function together, they may be considered as a single series, and each pair of steps at the same height and at the same end of the brush back and may be considered as a single step or seat.

35 The brush 27 is removably held in its seat 26 by manually removable screws 40, 40 which extend downwardly through the back 31 into threaded relationship with the bottom wall of the seat which is reinforced at that point to receive the screw. The screws pass through the brush back adjacent the steps or seats 35 so as to force the back directly downwardly. Positioned between the bottom of the brush seat and the brush back is an adjusting bar 36 which is provided at its opposite ends with pairs of shoulders 37, 37 which are spaced and positioned so as to cooperate with and support the brush back 31 by contacting seats thereon of the same height.

50 The adjusting bar 36 is adapted to be shifted along the brush back and accordingly is provided at one end with a plurality of screw holes 41 which, while interconnected, are so spaced that with the screw 40 positioned in one, it cannot accidentally pass to an adjacent hole. Centers of the screw holes are spaced apart by a distance equal to the spacing of adjacent seats 35 on the brush back, the relationship being such that the adjusting bar can be moved longitudinally of the brush back and retained in position by the screw 40 extending through the screw holes 41. Longitudinal movement of the adjusting bar 36 causes the shoulders 37 upon the bar to contact with seats or steps 35 at a different height upon the brush back and so positions the brush at a different radial position in the agitator body, the bottom of the bar lying on the seat bottom in the operative relationship, as illustrated.

70 When the brush element is new and the bristle tufts 34, 34 are of maximum length the adjusting bar 36 will be so positioned that it will contact and support the shoulders 35 which are uppermost on the brush back 31. This permits the brush to have its innermost radial position rela-

tive to the agitator body. As the brush bristles become worn the adjusting bar will, from time to time be adjusted so as to cooperate with shoulders or seats 35 which are lower upon the brush back 31. This will result in the brush back being held at a greater radial extension to compensate for the decrease in bristle length. Such adjustment requires in this embodiment, that the brush be removed from its seat.

The construction is one in which the adjustment is readily made and when made is permanent until the operator chooses to remake it. New brushes can replace the old brushes when no further adjustments are possible and the bristle wear has rendered the brush inoperative. All brushes will finally become inoperative when their bristle extension is not such that they extend to a radial distance which is substantially equal to that of the rigid beater bars 28, 28.

Referring now to Figures 10 to 12, inclusive, of the drawings, the second preferred embodiment of the invention is illustrated. In this embodiment the general appearance of the agitator and the arrangement of the brush elements relative to the beater elements is identical to that of the first embodiment as illustrated in Figure 2, and the difference in the embodiments lies in the means by which the radial adjustment of the brushes is obtained.

According to this second embodiment of the invention, when it is desired to adjust radially the brush element to compensate for bristle wear the retaining screws 40, 40 are loosened sufficiently to permit the brush 27 to be shifted longitudinally, or more accurately helically, in the brush seat 26 so that lower shoulders 35 upon the brush back may engage the adjuster bar shoulders 37 which, in this embodiment, are fixedly positioned in the bottom of the brush seat. Each screw 40 extends in threaded relationship into a nut 45 which is slidably carried in a guide-way 46 on the underside of the bottom wall of the brush seat to permit the screw to be shifted with the brush. The second embodiment is characterized by the advantage that radial adjustment can be obtained without removing the brush from the agitator.

Referring now to Figures 13 to 16, inclusive, the third preferred embodiment of the invention is illustrated. As in the case of the second embodiment, it is not necessary to remove the brush in order to obtain radial adjustment. The removable helically extending brush 27 with its rigid back 31 is again retained within the helically extending brush seat 26 by screws 40, 40 which extend into reinforced portions of the bottom of brush seat. The brush back is again formed with a series of sloping seats 35, 35 characteristic of the first two embodiments. The adjuster bar, in the present embodiment, is indicated by the reference character 50 and is formed with an upwardly extending lever 51 formed as a pointer at its end which extends upwardly adjacent the side of the brush seat near the longitudinal midpoint thereof, as illustrated in Figure 15, and ends adjacent a series of spaced numerals positioned upon the agitator surface, as illustrated in Figure 16. Adjuster bar 50 is provided at its ends with the supporting shoulders 37, 37 which cooperate, as in the two previous embodiments with the brush back seats 35. In this instance, however, the bar is formed with extended slots 52 through which the screws 40 extend, the relationship being such that with the screws loosened sufficiently it is possible, by

means of a shifting force applied to the adjusting lever 51 to shift the adjuster bar 50 to bring the supporting shoulders 37 thereof into contact with the shoulders 35 upon the brush back which are lower thereon for the purpose of holding the back to a greater radial extension. With the brush securely secured in position by the screws 40, 40 the adjuster bar 50 is clamped in position relative to the back and to the seat and it is impossible for a change in adjustment to take place. As distinguished from embodiment 2 in which the brush was itself shifted longitudinally in order to accomplish radial adjustment, in the present embodiment it is the adjuster bar which is shifted longitudinally.

We claim:

1. In a rotary agitator for a suction cleaner, a part comprising a body including a helically extending brush seat, a part comprising a helically extending brush element in said seat, cooperating means to vary the radial extension of said brush element and comprising an angularly inclined support on one of said parts and a cooperating support on the other part, said supports being relatively adjustable longitudinally of said body and the position of said brush element in said seat being determined by the relationship of said supports, and means to secure said brush in said seat and the relative positions of said supports.
2. In a rotary agitator for a suction cleaner, a part comprising a body including a helically extending brush seat, a part comprising a helically extending brush element in said seat, cooperating means to vary the radial extension of said brush element and comprising a plurality of longitudinally adjustable seats at different heights on said brush element and a longitudinally adjustable seat-contacting support adapted selectively to contact said seats, and means to secure said cooperating means in fixed position and said element in said seat.
3. In a rotary agitator for a suction cleaner, a part comprising a body including a helically extending brush seat, a part comprising a helically extending brush element removably positioned in said seat, spaced supporting seats at various heights on said element, and supporting means adjustably positioned in said seat and adapted to contact selectively said supporting seats to vary the position of said element in said seat.
4. In a rotary agitator for a suction cleaner, a part comprising a body including a helically extending brush seat, a part comprising a helically extending brush element removably positioned in said seat, spaced supporting seats at various heights on said element, supporting means adjustably positioned in said seat and adapted to contact selectively said supporting seats to vary the position of said element in said seat, and means removably securing said element in said seat and said adjustable support in a fixed position.
5. A rotary agitator for a suction cleaner comprising a body rotatable about its major axis and including an elongated brush seat having a bottom wall, a brush element including a back and bristles positioned in said seat, cooperating relatively movable supporting means on said back and in said seat, the said means in said seat being carried by and longitudinally shiftable along said bottom wall, the said cooperating supporting means being so constructed and arranged that said brush is supported at different radial positions relative to said major axis in the different

longitudinal positions of said means in said seat, and manually operable means forcing said back into said seat and securing said cooperating means in a selected position.

6. A rotary agitator for a suction cleaner comprising a body, an elongated helically extending agitating element seat in said body, fixed means to support an agitating element in said seat, an elongated agitating element in said seat provided with longitudinally spaced supports at varying heights thereon adapted to cooperate selectively with the support means of said seat to position said element at a plurality of radial positions relative to said body, and adjustable means to retain said agitating element in adjusted position in said body.

7. A rotary agitator for a suction cleaner comprising a body, an elongated helically extending agitating element seat in said body, an elongated agitating element longitudinally and radially adjustable in said body, fixed means to support said agitating element in said seat, and support means at various heights on said agitating element adapted to cooperate selectively with said fixed means to adjust said agitating element radially as it is manually adjusted longitudinally, and means to retain said agitating element in adjusted position.

8. In a rotary agitator for a suction cleaner, a body, an elongated longitudinally extending helical seat fixedly positioned in said body, an elongated helical agitating element positioned in said seat, helically arranged cooperating supporting means on said body and said agitating element to adjust said agitating element radially in said body, one of said means being longitudinally movable relative to said seat, and manually adjustable means to secure said agitating element in adjusted position.

9. In a rotary agitator for suction cleaners, a rotatable body formed with a helically extending brush seat, a helically extending brush including a rigid helically extending rigid back positioned in said seat and of slightly lesser width than said seat, and brush tufts extended from said rigid back beyond said body, and means to adjust said element radially in said seat and relative to the axis of rotation of said body including means displaceable longitudinally relative to said back and positioned between said back and said seat.

10. In a rotary agitator for suction cleaners, a rotatable body formed with a helically extending brush seat, a helically extending brush including a rigid helically extending rigid back positioned in said seat and of slightly lesser width than said seat, and brush tufts extended from said rigid back beyond said body, and means to adjust said element radially in said seat and relative to the axis of rotation of said body comprising cooperating supporting means on said back and said seat, one of said means being arranged longitudinally relative to said back and

of varying heights longitudinally of said helically extending seat, said supporting means being adapted to cooperate selectively upon being shifted longitudinally relative to one another.

5 11. In a rotary agitator for suction cleaner, a body including an elongated brush seat, an elongated brush including a back and bristles positioned in and extended from said seat, brush-adjusting means slideable in said seat to adjust the radial position of said brush, and manually 10 operable means extended to the surface of said body adjacent said brush seat, operable from the exterior of said body, and shiftable longitudinally of said body to position said brush-adjusting means.

12. In a rotary agitator for a suction cleaner, a cylindrical body including an elongated helically extending brush seat, an elongated helical brush including a rigid back and bristles positioned in said seat, manually releasable means operable from the exterior of said body securing said brush in said seat, brush-height-adjusting means in said seat to adjust said brush radially, and manually operable means positioned adjacent said brush seat at the surface of said body and shiftable longitudinally relative thereto to position said brush adjusting means.

13. A suction cleaner rotary agitator having a major axis of rotation and including an elongated brush seat, a brush-adjusting element in said seat shiftable longitudinally of said agitator including portions adapted to contact a brush positioned in said seat, and manually operable positioning means connected to said brush-adjusting element and extended to the peripheral surface of said agitator and adapted to transmit a shifting force to said element.

14. In a suction cleaner rotary agitator, a body having an agitating element seat, an agitating element positioned in said seat and extended radially beyond said body, a plurality of means fixed to said body adapted to contact said element to determine the radial position thereof relative to the axis of agitator rotation, said element being shiftable lengthwise of said seat to contact selectively certain of said fixed means, and means cooperating with said fixed means to secure said element in said seat.

15. A rotary agitator for a suction cleaner comprising a body, an elongated agitating element seat on said body, an elongated agitating element in said seat and movable longitudinally thereof, cooperating supporting means on said element and said seat to position said element at various radial positions relative to the axis of rotation of said body in the various longitudinal positions of said element in said seat, and manually operable means to position fixedly said element and adapted to release said element to enable it to be adjusted to a new position.
